[57] CLAIM

The ornamental design for an optical enhancement backmount for a telescope, as shown.

DESCRIPTION

FIG. 1 is a front and side perspective view of an optical enhancement backmount for a telescope showing my new design, with the telescope and pivotal support unit being shown in broken line figures to illustrate the environment relationship of the backmount with a telescope;

FIG. 2 is a side elevational view thereof;

FIG. 3 is a rear elevational view thereof; and

FIG. 4 is a top plan view thereof.
